(57) **CLAIM**

The ornamental design for a jump starter, as shown and described.

DESCRIPTION

FIG. 1 is a perspective view of a jump starter showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the selected portion A in FIG. 1; and,

FIG. 9 is an enlarged view of the selected portion B in FIG. 1.

The broken lines shown in the drawings depict portions of the jump starter in which the design is embodied that form no part of the claimed design.

1 Claim, 9 Drawing Sheets
